UNITED STATES PATENT OFFICE.

JOSEPH T. MERCIER, OF CHICAGO, ILLINOIS, ASSIGNOR OF ONE-HALF TO WILLIAM S. MCCLAVE, OF CHICAGO, ILLINOIS.

HEATING APPLIANCE.

1,153,096.

Specification of Letters Patent.

Patented Sept. 7, 1915.

Application filed May 5, 1913, Serial No. 765,593. Renewed July 23, 1915. Serial No. 41,618.

To all whom it may concern:

Be it known that I, JOSEPH T. MERCIER, a citizen of the United States, residing at Chicago, in the county of Cook and State of Illinois, have invented certain new and useful Improvements in Heating Appliances, of which the following is a specification.

The present invention relates to a heating appliance adapted for use in buildings generally and particularly adapted for use in railway cars and similar traveling conveyances.

The objects of the present invention are to provide an equipment which will render the heating system simple and easy of control; which will produce a circulating body of hot water through the pipes of the radiator; which will utilize a single chambered member to receive fresh steam; establish a direct communication between the pipe for the fresh steam and the pipes of the radiator coils, and which will have a passage therein for the discharge of air and water of condensation from the coils, and which will have directly connected thereto a main discharge pipe for the system; and to arrange this chambered member together with all of its connections within the interior of the structure to be heated.

A further object of the invention is to produce an equipment for the purpose specified which is cheap of manufacture and durable of use, containing no involved mechanism or delicate parts which would be liable to get out of order.

The invention further consists in the features of construction and combination of parts hereinafter described and claimed.

In the drawings: Figure 1 is a perspective of the heating appliance of the present invention in operative position and with all attachments connected thereto; Fig. 2 a vertical section of the chambered member to which the steam and radiator pipes are connected, and through which the steam passes to the radiator pipes and into which the air and water of condensation passes from said pipes. Fig. 3 a section on line 3-3 of Fig. 2 looking in the direction of the arrows.

The present invention, as heretofore stated, relates to a heating appliance which may be used in buildings generally and which is particularly designed and adapted for use upon traveling conveyances, as for instance

sleeping cars, railroad coaches, etc. In this latter field considerable difficulty has been experienced in providing a heating system which will heat the car quickly, which will maintain the heat in the car at an even temperature, and which will hold the heat for any substantial length of time after the steam supply has been cut off, and which will be sufficiently strong and compact to withstand the jolting and jarring incident to use, without becoming disordered.

The present invention operates so as to quickly eject the air from the pipes of the radiator coil and fill the same with steam, then allow the steam to condense and accumulate in a water of condensation chamber and then allow this water of condensation to enter the steam chamber where it becomes heated and rises, thus maintaining a circulation through the pipes of the radiator, as will be more fully explained hereinafter. The initial entering of the steam through the pipes will effect the quick heating of the car desired, and the accumulation and circulation of hot water will produce a heat which is even and bring about a condition so that when the supply of steam is cut off from the car the heat stored within the coils will be given off for a considerable period of time thereafter. All of the connections for the entrance of steam into and the discharge of air and water of condensation from the pipes of the radiator are made to a single chambered member located within the structure to be heated.

The present invention further eliminates all delicate valves and multiplicity of casting which might complicate and render easy of disorder a heating system.

Referring to the drawings, and more particularly to Fig. 1, a radiator coil is there shown consisting of an upper pipe 4, a middle pipe 5, and a lower pipe 6, although the number and size of these pipes may be varied in accordance with the ideas of the manufacturer. As shown there are a set of 100 pipes extending in opposite directions from a casting 7, although the particular arrangement of the casting and pipes may be varied. Each set of pipes has its outer ends connected to a bend or connection 8 of any suitable style, the inner ends of which set of pipes are connected to the casting 7, and suitable bosses 9 are provided on said casting to re-

ceive said pipes. The casting 7 in the construction shown is of an integral L-shaped formation consisting of what may be termed a vertical portion 10 and a horizontal portion 11.

5 By referring to Fig. 2 it will be seen that this casting is of a chambered nature, and that it is provided on its interior with a horizontally extending cross wall 12, and a vertical cross wall 13, which latter merges into the horizontal cross wall. These cross walls divide the interior of the chambered casting or member into a steam chamber 14, and an air and water of condensation chamber 15. The steam chamber consists of a vertically extending passage 16 which merges into the main portion of the steam chamber and said main portion of the chamber occupies the upper portion of the casting. 10 In the construction shown a protuberance 17 is formed on the casting and this protuberance is chambered and forms a portion of the steam chamber. The chamber in the boss communicates with the upper portion 18 of the vertical portion of the casting 7, or in other words with the main steam chamber, and the pipes 4 and 5 of the steam coil are in direct communication with this upper portion 18; that is they are in 15 direct communication with the steam chamber.

30 A steam supply pipe 19 is provided, which enters, and is directly connected with the front of the horizontal portion 11 of the casting 7, and has communication with the steam chamber through a port or opening 20 formed in a wall 21 within the casting. It will be noticed that the port 20 is of a tapered formation, a shiftable valve 22 is 35 provided having seating face 23 adapted to seat against the walls of the port 20, and close communication between the steam pipe and the steam chamber, cutting off the flow of steam to the pipes of the radiator. This 40 action, however, will be more fully explained hereinafter. When steam is initially admitted to the system, the pressure of the same will force the valve 22 into the position shown in Fig. 2, opening the port 20 and 45 allowing steam to pass into the steam chamber 14 of the casting 7, and into the pipes 4 and 5 of the radiator coils, the lowermost pipe 6 of said coils communicates directly with the air and water of condensation discharge chamber 15, and said discharge chamber, as will be seen by referring to Fig. 2 is positioned in the lower rear portion of the casting 7. A main discharge pipe 24 50 communicates directly with this discharge chamber.

55 The casting is provided with oppositely disposed bosses 25 at its lower end. Into one of these bosses enters the forward end of the discharge pipe 24. In practice only one discharge pipe will be employed, so that when

said pipe is affixed, a plug 26 will be inserted into the opening in the other boss 25. I provide bosses on each side so that the discharge pipe may be connected to either side of the casting desired. This feature is 70 made by reason of the fact, that in installing the appliance it may become necessary to vary the position of the discharge pipe in order to avoid interference by legs of the car seats, etc.

75 The steam pipe 19 and the discharge pipe 24 are each provided with controlling valves 27. These valves may be of any suitable nature. It is only necessary to provide some sort of valve which will satisfactorily control the admission of steam, and some sort of valve which will satisfactorily permit of the discharge of air and water of condensation. No claim is made in the present case to any particular form of valve for use in this respect, and it is expressly understood that the invention is in no wise limited to any particular type of valve this feature being entirely optional with the builder or 80 user.

85 As shown in the drawings a cross or division wall 28^a is placed opposite the points of communication of the pipes 6 with the discharge chamber. This is to insure a deflection of the air and water coming from the 90 pipe 6 to the forward part of the chamber and into the discharge pipe 24. The valve 22, as heretofore stated, is of a shiftable nature and comprises the seating face 23 heretofore referred to which may be termed the 95 front seating face, and a seating face 28 which may be termed the rear seating face, and which in the construction shown, is of a flat nature, and has a greater square area of exposed surface than the front seating face. 100

105 The division wall 13 is provided with an opening 29, the walls of which are threaded, and into which is inserted a ring 30 threaded to mesh with the threaded walls of the opening, and this ring in the construction 110 shown is provided with a series of rearwardly extending webs 31 terminating in a hub 32, and this hub forms a bearing for a stem 33 attached to the valve member 22, which stem has a sliding fit within said hub. 115 The provision of the ring 30 is necessitated in order to assemble the valve in position. In assembling the valve the same is placed in the chamber 14 through the opening 29 in the wall 13, and after being so placed the 120 ring 30 is secured into position, reducing the size of the opening 29, and thus locking the valve in position within the space 16.

125 By referring to Fig. 2 it will be clearly observed that the flat or rear face 28 of the valve member 22 is in communication with the discharge chamber 15, and the forward tapered surface 23 of the valve member is in communication with the steam pipe 19. Upon the initial operation of the system 130

the pressure of the steam from the pipe 19 will force the valve over into the position shown in Fig. 2, but as the water of condensation accumulates within the chamber 5 15 the pressure of this water will act upon the face 28, and when said pressure has become greater than the pressure of the steam from the pipe 19, said valve will be shifted so as to seat the face 23 and cut off further 10 entrance of steam into the steam chamber. This will establish communication between the condensation chamber 15 and the steam chamber 14 through the opening 29 and passage 16. Some of the water from the condensation chamber will then flow into the steam chamber 16. This steam chamber is hot from the action of the steam, and the water from the condensation chamber when it enters the hot steam chamber will be increased 20 in temperature and will rise. After a relatively small quantity of water has flowed from the condensation chamber to the steam chamber, the pressure in the condensation chamber will have dropped sufficiently 25 so that the pressure in the steam pipe 19 is greater than in the condensation chamber, and the valve will again shift back to the position shown in Fig. 2. Steam will again enter, and continue to enter, until the 30 pressure in the condensation chamber is greater than the pressure in the pipe 19, when the valve will again shift allowing another quantity of water to enter the steam chamber from the condensation chamber, 35 which water will become heated and rise as previously explained. This follows the well known principle of hot water circulation in which a circulating pipe is provided together with means for applying heat to the 40 pipe at a particular point. The heat will cause the water to rise at its point of application to the pipe, so that it ascends on one side of the circulating pipe and descends on the other with the result that a circulation 45 is established. In the present case the steam chamber is the point of application of heat while the pipes 4, 5, and 6, together with the union 8, are the circulating pipes. To summarize the foregoing, the circulation is 50 established by alternately allowing relatively small quantities of water to enter into the heated steam chamber followed by the admission of steam into the steam chamber whereby the circulation of water through 55 the pipes of the coil is maintained.

From the foregoing description it will be seen that by a single simple casting, provision is made for allowing steam to enter into the coils, for discharging air from the 60 coils, for circulating water of condensation through the coils, and for discharging said water of condensation, and that a direct connection is established between this casting and the main steam pipe and main discharge pipe, bringing into one single

compact member all of the means which are necessary to the working of the heating system.

Where statements are made concerning differences in pressure upon the steam side 70 and the water of condensation side of the valve 22, this is understood not to mean an actual difference in pounds pressure as between the train pipe and the coil, but is the difference in pressure brought about owing 75 to the increased area of the face of a valve 22 on the water of condensation side from the area on the steam side of said valve.

It is understood that the present appliance produces a circulating system, and that 80 the hot water is circulated through the pipes even after the steam is cut off. This is owing to the fact that the two upper pipes are hotter than the lower pipe, and the hot water from the upper pipes traveling through the same and into the lower pipe will force the colder water from the lower pipe up into the upper pipes and thus the circulation is maintained. 85

I claim:

1. In a heating appliance, the combination of means affording a steam chamber and a water of condensation chamber, a main steam supply pipe communicating with the steam chamber, a series of pipes having 90 one end thereof communicating with the steam chamber and the other end communicating with the condensation chamber, and means actuated by differences in pressure within the steam chamber and condensation 95 chamber for simultaneously establishing communication between said chambers and cutting off communication between the supply pipe and steam chamber when moved into one position, and for simultaneously 100 cutting off communication between said chambers and establishing communication between the supply pipe and steam chamber when moved to another position, substantially as described. 105

2. In a heating appliance, the combination of means affording a steam chamber and water of condensation chamber, a main steam supply pipe communicating with the steam chamber, a series of pipes having one 110 end thereof communicating with the steam chamber and the other end communicating with the condensation chamber, a shiftable member actuated by differences in pressure within the steam chamber and condensation 115 chamber for simultaneously establishing communication between said chambers and cutting off communication between the supply pipe and steam chamber when moved into one position, and for simultaneously cutting off communication between said chambers and establishing communication between the supply pipe and steam chamber when moved into another position, substantially 120 as described. 125

3. In a heating appliance, the combination of a single casing having a steam chamber and a water of condensation chamber therein, a main steam supply pipe communicating with the steam chamber, a series of pipes, the lowermost pipe thereof communicating with the water of condensation chamber, the remainder of the pipes communicating at one end with the steam chamber and at 10 their other end with the lowermost pipe, means actuated by differences in pressure within the steam chamber and condensation chamber for simultaneously establishing communication between the said chambers and cutting off communication between the steam chamber and supply pipe when moved into one position, and for simultaneously cutting off communication between the steam chamber and water of condensation chamber and establishing communication between the supply pipe and steam chamber when moved into another position, substantially as described.

4. In a heating appliance, the combination 25 of a single casing having a steam chamber and a water of condensation chamber therein, a main steam supply pipe communicating with the steam chamber, a series of pipes, the lowermost pipe communicating with the water of condensation chamber, the remainder of the pipes communicating at one end with the steam chamber and at their other end with the lowermost pipe and a shiftable member actuated by differences 30 in pressure within the steam chamber and condensation chamber for simultaneously establishing communication between said chambers and cutting off communication between the supply pipe and steam chamber 35 when moved into one position and for simultaneously cutting off communication between the steam chamber and water of condensation chamber and establishing communication between the supply pipe and 40 steam chamber when moved into another position, substantially as described.

5. In a heating appliance, the combination of means affording a steam chamber and a water of condensation chamber, a main 50 steam supply pipe communicating with the steam chamber, a series of pipes having one end thereof communicating with the steam chamber and the other end communicating with the water of condensation chamber, a 55 shiftable member actuated by differences in pressure within the steam chamber and condensation chamber for simultaneously establishing communication between the said chambers and cutting off communication 60 between the supply pipe and steam chamber when moved into one position, and for simultaneously cutting off communication between said chambers and establishing communication between the supply pipe and 65 steam chamber when moved into another

position, and said shiftable member presenting a greater exposed area toward the water of condensation chamber than toward the steam chamber, substantially as described.

6. In a heating appliance, the combination 70 of a single casing having a steam chamber and a water of condensation chamber therein, a main steam supply pipe communicating with the steam chamber, a series of pipes, the lowermost pipe communicating 75 with the water of condensation chamber, the remainder of the pipes communicating at one end with the steam chamber and at their other end with the lowermost pipe, a shiftable member actuated by differences in pressure 80 within the steam chamber and condensation chamber for simultaneously establishing communication between said chambers and cutting off communication between the steam chamber and supply pipe when moved in one direction and for simultaneously cutting off communication between the steam chamber and water of condensation chamber 85 and establishing communication between the supply pipe and steam chamber when moved in the other direction, and said shiftable member presenting a greater exposed area 90 toward the water of condensation chamber than toward the steam chamber, substantially as described.

7. In a heating appliance, the combination 95 of a casing divided in its interior to form a steam chamber along the forward and upper portions thereof and a water of condensation chamber along the lower portion 100 thereof, a main steam supply pipe communicating with the steam chamber, a series of circulating pipes, the lowermost pipe communicating with the water of condensation chamber, the remainder of the 105 pipes communicating at one end with the steam chamber and at the other end with the lowermost pipe, and means actuated by differences in pressure within the steam chamber and condensation chamber for 110 simultaneously establishing communication between the water of condensation chamber and steam chamber and cutting off communication between the steam supply pipe and steam chamber when moved in one direction 115 and for simultaneously cutting off communication between the steam chamber and water of condensation chamber, and for establishing communication between the supply pipe and steam chamber when moved into the 120 other direction, substantially as described.

8. In a heating appliance, the combination 125 of a casing divided in its interior to form a steam chamber along the forward and upper portions thereof, and a water of condensation chamber along the lower portion thereof, a main steam supply pipe communicating with the steam chamber, a series of circulating pipes, the lowermost pipe communicating with the water of condensa- 130

tion chamber, the remaining pipes communicating at one end with the steam chamber and at the other end with the lowermost pipe, and a shiftable member actuated by differences in pressure within the steam chamber and condensation chamber for simultaneously establishing communication between the water of condensation chamber and steam chamber, and cutting off communication between the steam supply pipe and steam chamber when moved in one direction, and for simultaneously cutting off communication between the steam chamber and water of condensation chamber, and for establishing communication between the steam supply pipe and steam chamber when moved in the other direction, substantially as described.

9. In a heating appliance, the combination of a casing, divided in its interior to form a steam chamber along the forward and upper portions thereof, and a water of condensation chamber along the lower portion thereof, a main steam supply pipe communicating with the steam chamber, a series of circulating pipes, the lowermost pipe

communicating with the water of condensation chamber, the remainder of the pipes communicating at one end with the steam chamber and at the other end with the lowermost pipe, a shiftable member actuated by differences in pressure within the steam chamber and condensation chamber for simultaneously establishing communication between the water of condensation chamber and steam chamber, and cutting off communication between the steam supply pipe and steam chamber when moved in one direction, and for simultaneously cutting off communication between the steam chamber and water of condensation chamber and for establishing communication between the steam supply pipe and steam chamber when moved in the other direction, and said shiftable member presenting a greater exposed area toward the condensation chamber than toward the steam chamber, substantially as described.
